(57) **CLAIM**

The ornamental design for an LED tree, as shown and described.

DESCRIPTION

FIG. 1 is a perspective view of an LED tree in accordance with one aspect of the design;

FIG. 2 is a top plan view of the LED tree of FIG. 1;

FIG. 3 is a side elevational view of the LED tree of FIG. 1 showing the LED assembly in broken lines;

FIG. 4 is a side elevational view of the LED tree of FIG. 1;

FIG. 5 is a bottom plan view of the LED tree of FIG. 1;

FIG. 6 is a side elevational view showing the LED assembly in a partially unfolded LED tree;

FIG. 7 is a side elevational view of a partially unfolded LED tree; and,

FIG. 8 is a side elevational view of the LED tree in a closed configuration.

The parts shown in broken lines in FIGS. 1-8 form no part of the claimed design.

1 Claim, 5 Drawing Sheets
